HAND WEAVING DEVICE

Hyman M. Zippel, Philadelphia, Pa.

Application February 24, 1947, Serial No. 730,233

17 Claims. (Cl. 139—34)

1

This invention relates to an improvement in hand weaving devices which can readily be handled while in use and which can readily be stored when not in use.

One of the objects of my invention is the provision of a device of this character in which the warp threads are first laid on a supporting board in accordance with the desired pattern, after which the weft threads are interwoven with the warp threads to complete the article.

Another object of my invention is the provision of a device of this character whereby various decorative figures may be woven in the body of the article and which may be woven before the warp threads are laid for the body of the article and which warp threads are interwoven with the warp threads of the body portion, and in which the figures are so positioned that when the weft threads are interwoven with the warp threads they may also be interwoven with the weft threads of the design.

Another object of my invention is the provision of means whereby small designs may be woven on separate members then successively positioned on a supporting member on which the body of the article is woven and interwoven in the body of the article during the weaving of the body.

Another object of my invention is the provision of means whereby strips or blocks of predetermined sizes may be woven with or without decorative figures and then secured to each other by weaving, crocheting or other means to form the completed article.

Having now described in a general way the nature and purpose of the invention, I will proceed for illustrative purposes, to a detailed description of several devices for weaving in accordance with my invention, with reference to the accompanying drawings, in which:

Fig. 1 is a plan view on a reduced scale of one form of support on which a plurality of blocks are removably mounted, some of which have been broken away to illustrate the manner of mounting the blocks thereon;

Fig. 2 is a sectional view on a larger scale of a portion of the support and blocks on the line 2—2 of Fig. 1;

Fig. 3 is an end view of another form of support for blocks such as shown in Figs. 1 and 2;

Fig. 4 is a sectional view on the line 4—4 of Fig. 3;

Fig. 5 is an end view of a portion of another form of support;

Fig. 6 is a sectional view on the line 6—6 of Fig. 5;

2

Fig. 7 is a face view of a portion of a piece of material woven on a weaving device;

Fig. 8 is a plan view of a piece of fabric on a large scale such as shown in Fig. 7;

Fig. 9 is a view of a needle for positioning the yarn during the weaving;

Fig. 10 is a side elevation of a disc which may be mounted on a warp beam;

Fig. 11 is a diagram illustrating the laying of the warp to be wound on a beam in connection with a structure such as shown in Figs. 1 and 2; and

Fig. 12 is a similar diagram for laying up warp to be wound on a beam for forming a strip on a structure such as shown in Figs. 5 and 6.

Referring first to Figs. 1 and 2, the most simple form in which I have shown a board 10 on which peg supporting blocks 12 are mounted, each being provided with a plurality of equally spaced openings 14 for the reception of warp and weft threads retaining pegs 16.

The openings along the edges of each block are spaced one half the distance from the edges of the blocks as the spacing of the openings in the bodies 25 of the blocks so that the spacing of the openings in the assembled blocks in which pegs are inserted are equally spaced in both longitudinal and transverse directions regardless of the number or positions of the blocks mounted on the board or support. The blocks are preferably formed of 30 resilient material so as to hug the inserted pins, and formed between the openings are longitudinal and transverse V-shaped grooves 18 on both sides of the body portion forming projections whose walls taper outwardly from the body, as clearly 35 shown in Figs. 1 and 2 which form spaces between the laid warp threads for the free passage of a weft carrying needle 40 under the warp threads during the weaving as hereinafter described.

The board 10 is preferably provided with lines such as indicated at 20 in Fig. 1, indicating the 40 positions in which the blocks 12 are positioned; while the reference character 17 designates a series, preferably five holes at each corner formed

by the lines 20, whereby the blocks are secured to the board by means of pegs 16 entering holes 17 in the board. If the holes for the block positioning pegs are not to be used for thread supporting pegs, the heads of the pins do not extend above 45 the upper faces of the blocks 12 as shown at the right hand side of Fig. 2, but, if pegs are to be used for securing the blocks to the boards as well as for holding threads, extra long pegs 16' are used as shown in Fig. 2.

In Fig. 7, I have shown diagrammatically a strip

of fabric 22 the length of four blocks and the width of three blocks, in the central portion of the space of each block a design 24 has been woven of a color different from that of the body portion in the blocks, which designs may differ in color from each other.

In Fig. 1, the upper face of only one of the blocks 12 has been completed, while on the others only the centers for the peg openings have been indicated, but it is to be understood that the upper face of each block is shaped like the face of the single completed block.

I preferably form blocks three inches square, and, assuming a nineteen inch square board was used, six blocks each way could be mounted thereon or thirty-six blocks.

Assuming it was desired to weave a strip the width of three blocks and six blocks in length with a single design in the strip or a plurality of designs as shown in Fig. 7.

If the area of the design or of each design is that of a block or less than a single block, pegs designating the outline of the design may be placed in the openings 14 of the blocks, while in any position on the board and the design woven thereon by first laying one set of threads on the pegs and then interweaving the other or cross threads therewith leaving the ends of the threads free to be interlocked or connected with the body forming threads. After the designs have been woven on the blocks, they are positioned at the proper positions on the board 10 or may be positioned before the weaving is done, and, after being properly positioned, blocks are positioned on the board to permit the placing of a complete row of pins along each marginal edge of the strip to be woven.

The warp threads for the body forming portions are first laid by extending the through threads on the sides of the design from end to end of the blocks, while those in the line of the design are merely laid from the edge pegs to the marginal pegs forming the design or from the marginal pegs of one design to an adjacent design.

After the warp threads have been laid, the through weft threads are woven from edge to edge of the strip, then between the edges of the designs and then from the edges of the strip to the outer margin of a design, and then from the inner margins of one design to the inner margin of an adjacent design or in any other desired order.

If it is desired to form a strip of greater length than the length of the board, several strips may be woven as above described and secured to each other by crocheting or by weaving a strand through the loops which engage the pegs.

A second strip may be formed integral with the first strip by placing the warp loops which surround the lower pegs along the lower edges of the lower blocks and looping them on the pegs at the upper edge of the upper blocks and then passing each warp thread around the pegs and through the loop thereon during the laying of the warp for the next strip and repeating the weaving, as above described.

In Figs. 3 and 4, I have shown a modified form in which a warp beam 26 is mounted for rotation on removable spindles 27 in brackets 28 connected to each other by a cross member 28', while the brackets are connected to the bottom of the board 10 by screws 28'' which are provided with knurled heads. The beam is provided with end flanges 29, and located between each flange and the adjacent bracket 28 is a spring member 32 for

maintaining a braking action on the beam to maintain the warp threads taut.

The beam may be provided with fixed discs 31 spaced equally with the pegs in the blocks the full length of the beam, and may be provided with slots 33 into which the loops of the warp threads are slipped as hereinafter described.

One method of winding warp on the beam for weaving a plain strip, without designs, is as follows:

The brackets 28, together with the cross-bar 28', are disconnected from the board 10 by removing the screws 28''. The board 10 is provided with end transverse rows 101 and 102 with intermediate rows therebetween, which extend across the full width of the board. The board 10, together with the blocks thereon, is then positioned on a table or other support with the beam parallel to the transverse rows of blocks, as shown in Fig. 11, with the discs 31 in the plane of the longitudinal rows of openings for the pegs and in the beam 26^a at a distance from the peg 16 slightly greater than the length of the strip to be woven. Additional pegs are then positioned in each of the openings in the transverse row in which the peg 16 is positioned, about which the warp threads for the strip are looped. The end of the thread for forming the warp is connected to peg 16 and the thread is then looped in the slot 33 of disc 31 in the plane of said peg to form the first warp, the thread is carried back and looped around the peg next to peg 16 to lay the second warp thread, then back to the beam and looped in the slot in the next disc to lay the third warp thread, which operation is repeated during the laying of the warp threads for the entire width of the strip to be woven, the other end of the thread being secured to a peg or a disc.

After the through warp threads have been placed on the pegs 16 and the discs 31, the beam is wound counterclockwise to wind the warp on the beam between the various discs and during the winding the board and beam are drawn towards each other, the winding is continued until only sufficient unwound warp is left to permit the positioning of the board 10 over the brackets and securing the board to them by means of the screws 28'', the remaining slack is then wound on the beam by a counter-clockwise movement of the beam 26^a, so that the threads will then extend from the underside of the beam, around the board 10, over transverse row 101 to the pegs in the transverse line with peg 16 in the openings in the blocks in transverse row 102 of blocks. Pegs are then placed in the row of openings along the outer edge of blocks in the transverse row 101, as well as in each opening in the vertical lines at the vertical edges of the strip to be woven.

After the warp has been wound on the beam, the weft is interwoven with the warp over the entire length of the blocks set up on the board, and, after the full length has been woven, the woven fabric on the rows of blocks beyond the row 101 is removed from the pegs and the blocks in row 102 with the pegs therein are removed from the board 10, the blocks in row 101 with the fabric on the pegs are positioned to replace transverse row 102 with fabric across the entire face of each of the blocks in the row, while the blocks removed from row 102 are positioned to form row 101 and, if the pegs have not been removed, the blocks can be reversed to position pegs along the longitudinal edges of the strip being woven as well as along the left hand edge of the row of blocks 102, the beam 26^a being turned by the withdrawal of thread

during the transfer of the row of blocks to their new positions to form row 12. Weft threads are then interwoven successively on the block in the rows from row 102 through row 101, and a similar transfer of blocks is made, which process is repeated throughout the weaving of the strip.

It is desired to weave designs of the color of the warp and another color, pegs are inserted in predetermined blocks forming the outlines of the designs, and a weft thread of a color, other than the ground, is interwoven with the warp within the outline of the designs formed by the pegs, and looped about pegs of the design outlines, ground colored weft threads are then interwoven with the warp threads on the exterior of the outline of the pegs and looped with loops of the design weft threads around the design outline pegs.

In Figs. 5 and 6, I have shown another modified form of device in which arc-shaped blocks 12^a are mounted on a cylinder 10^a in the same manner as blocks 12 are mounted on board 10 in the structure shown in Figs. 1 to 4.

The blocks 12^a may be molded to form but I prefer to use blocks such as shown in cross section in Fig. 2 in which the blocks are curved about the cylinder and which may be used on cylinders of different diameters whose peripheries are such as to receive the desired number of blocks edge to edge so that the transverse rows of pins in adjacent blocks are equal to those in the bodies of the blocks. When such blocks are curved on a cylinder the openings therethrough will extend in radial directions and match with radially extending openings in the cylinders, the spacing varying around the periphery in accordance with the curving of the blocks, decreasing from the largest diameter to the smallest diameter of cylinders.

The beam 26^a may also be provided with properly spaced discs 31^a, the cylinder 10^a and a beam 26^a are rotatably mounted in standards 28^a connected to each other by a cross member 28^a as in the structure shown in Figs. 3 and 4, the beam 26^a also being frictionally held by springs 32^a.

The standards 28^a are each provided with a groove 35 through which the ends of shaft 27^a to which the beam 26^a is secured may be removed to permit the beam to be positioned for the reception of warp threads of greater length than required for the blocks on the cylinder.

In order to retain the cylinder 10^a fixed while weaving, a reduced end 34 of the cylinder is provided with a series of spaced openings 36, and the bracket 28^a is provided with an opening with which the openings 36 can be brought in register, and 38 is a pin in the opening in bracket 28^a adapted to be entered in the openings 36 to lock the cylinder to the brackets.

In the form shown in Figs. 5 and 6, strips of at least four blocks in length can be woven by directly laying the through warp threads around the blocks, with the loops at both ends surrounding the same row of warp retaining pegs or longer strips can be formed by weaving strips of four block lengths to each other as on the board or support in Figs. 1 and 2.

Continuous strips may also be woven as with the structure shown in Figs. 5 and 6, but without transferring the blocks with the woven fabric from one position to another as is done with the board in Figs. 3 and 4.

In weaving a continuous strip on a cylindrical structure having four blocks as in Figs. 5 and 6, the proper length of warp threads is measured and wound on the beam as shown in Fig. 12.

The shaft 27^a together with the beam 26^a thereon is removed from the standards 28^a through the slots 35 in the standards and positioned in standards 28^b in slots 35^a therein, then positioning the standards 28^a and 28^b the required distance from each other with the axis of the beam parallel with the axis of the cylinder to provide the proper length of warp for the strip to be woven.

- 10 The warp threads are then laid between a row of pegs 16 in one of the blocks on the cylinder 10^a and discs 31^a on the beam 26^a as described in connection with Fig. 11 and after the warp threads have been laid, they are wound on the beam and the beam is transferred from the standards 28^b to the standards 28^a and all of the slack in the warp is taken up so that the warp threads extend from the beam 26^a to the cylinder 10^a as shown in dotted lines in Fig. 6.
- 15 After the warp has been wound on the beam, weaving of the weft with the warp over at least three blocks may be completed and a transverse row of pegs may be placed in the fabric as described in connection with the weaving on the structure shown in Figs. 3 and 4.

The fabric may then be removed from the row of blocks on which the weft was first woven with the warp, and then weaving the weft with the warp on the fourth row, after which the fabric can be removed from the second row of blocks, then again weaving the weft on the next row (or the row on which the weft was first woven), and repeating this procedure leaving fabric on two rows of blocks between the row just cleared of fabric and the row on which the weft is to be woven.

Tubular members of various diameters may be woven by providing cylinders of the desired diameters for the reception of the proper number of blocks 12^a for forming the tube.

- 20 A tubular member, such as a sleeve, of a diameter substantially that of the periphery of an annular set of four blocks 12^a, mounted on a cylinder 10^a, such as shown in Fig. 6, and a sufficient number of annular sets across the cylinder, as shown in Fig. 5, to form the desired length of the tube, may be woven by placing a peg in each of two annular rows of openings spaced from each other, the distance substantially that of the length of the tube to be woven. One row of pegs may be positioned in openings to form the margin of the cuff of a sleeve at one end of the tube, while the other row may be positioned to form an edge on the other end of the tube to be seamed to the arm hole in a woven garment. The warp threads are laid, for example, by securing the end of the thread to any peg in the right-hand annular row, carrying the thread across the cylinder, looping the thread in a clockwise direction about the peg in the next transverse row of holes in the left-hand annular row of pegs, then looping the thread in the reverse direction about the peg next to the peg to which the end of the thread is secured, and continuously carrying the thread back and forth and looping about each successive peg in the annular rows except the last peg in the left-hand row (the peg in the row to which the thread was fastened) and securing the other end of the thread to the last peg, so that an uneven number of warp threads is laid across the blocks. The weft threads are then interwoven round after round with the transverse warp threads from one end of the tubular member to the other.
- 25 After all of the weft threads have been inter-
- 30
- 35
- 40
- 45
- 50
- 55
- 60
- 65
- 70
- 75

woven with the warp threads, the woven tube can readily be removed by first removing all of the pegs securing the blocks to the cylinder, the tendency of the blocks to assume their original form will stretch the woven tube slightly so that the blocks and tube can readily be stripped from the cylinder.

If it is desired to break up a straight line seam, the pegs about which the warp threads are to be wrapped may be laid in any desired order so long as there is a warp holding peg in each annular row of openings to form the full length of the tube to be woven.

In the foregoing, I have described several ways of weaving, but it will be appreciated that after the majority of persons have become acquainted with either device, they will develop various methods of their own, both for weaving strips and blocks as well as designs of articles for which they may lay out patterns on cross-line paper for weaving various types of wearing apparel which may be woven to exact sizes as well as shapes which may be woven in flat form and seamed together or in tubular form with or without seams.

It will be evident that numerous variations in the structure of the invention may be made without departing from the principles thereof as defined in the following claims.

What I claim and desire to protect by Letters Patent is:

1. A device of the character described comprising a support having a plurality of equally spaced holes in rows at right angles to each other for the reception of pegs about which warp and weft threads are adapted to be wound during weaving, the distance between one edge of the support and the adjacent row of holes being substantially equal to one half the distance between adjacent rows of holes.

2. A device of the character described comprising a support formed of resilient material having a plurality of equally spaced holes in rows at right angles to each other for the reception of pegs about which warp and weft threads are adapted to be wound during weaving, the distance between two edges of the support and the adjacent row of holes being substantially equal to one half the distance between adjacent rows of holes.

3. A device of the character described comprising a rectangular support having a plurality of equally spaced holes in rows at right angles to each other for the reception of pegs about which warp and weft threads are adapted to be wound during weaving, said rows of holes being parallel to the edges of the support, the distance between three edges of the support and the adjacent row of holes being substantially equal to one half the distance between adjacent rows of holes.

4. A device of the character described comprising a square support having a plurality of equally spaced holes in rows at right angles to each other for the reception of pegs about which warp and weft threads are adapted to be wound during weaving, said rows of holes being parallel to the edges of the support, the distance between each edge of the support and the adjacent row of holes being equal to one half the distance between adjacent rows of holes, whereby a plurality of supports may be assembled so that the distance between adjacent rows of holes of two supports placed side by side are as equally spaced from each other as those in the other portions of the supports.

5. A device of the character described comprising a supporting base and a plurality of rectangular blocks each having a plurality of equally spaced holes in rows at right angles to each other and parallel to the edges of the blocks for the reception of pegs about which warp and weft threads are adapted to be wound during weaving, the rows of holes along the edges of the edges of adjacent blocks being spaced the same distance from each other as from other adjacent rows, some of the holes at each corner of each block extending through the blocks, the supporting base having designated openings therein registering with the through openings in the blocks for the reception of pegs extending through the blocks for securing the blocks in predetermined positions on the base member.

6. A device of the character described comprising a supporting base and a plurality of rectangular blocks each having a plurality of equally spaced holes in rows at right angles to each other and parallel to the edges of the blocks for the reception of pegs about which warp and weft threads are adapted to be wound during weaving, 25 the rows of holes along the edges of the edges of adjacent blocks being spaced the same distance from each other as from other adjacent rows, some of the holes at each corner of each block extending through the blocks, the supporting base having designating means including openings therein registering with the through openings in the blocks for the reception of pegs extending through the blocks for securing the blocks in predetermined positions on the base member.

7. A device of the character described comprising an annular rotatably mounted supporting base and a plurality of rectangular arcuate blocks each having a plurality of equally spaced holes in rows at right angles to each other and parallel to the edges of the blocks for the reception of pegs about which warp and weft threads are adapted to be wound during weaving, the rows of holes along the edges of the adjacent blocks being spaced the same distance from each other as from other adjacent rows, some of the holes at each corner of each block extending through the blocks, the supporting base having designating means including openings therein registering with the through openings in the blocks for the reception of pegs extending through the blocks for securing the blocks in predetermined positions on the base member.

8. A device of the character described comprising an annular rotatably mounted supporting base and a plurality of rectangular arcuate blocks each having a plurality of equally spaced holes in rows at right angles to each other and parallel to the edges of the blocks for the reception of pegs about which warp and weft threads are adapted to be wound during weaving, the rows of holes along the edges of the edges of adjacent blocks being spaced the same distance from each other as from other adjacent rows, some of the holes at each corner of each block extending through the blocks, the supporting base having designating means including openings therein registering with the through openings in the blocks for the reception of pegs extending through the blocks for securing the blocks in predetermined positions on the base member.

9. A device of the character described comprising an annular rotatably mounted supporting base and a plurality of rectangular arcuate blocks 60 to be wound during weaving, the rows of holes along the edges of the edges of adjacent blocks being spaced the same distance from each other as from other adjacent rows, some of the holes at each corner of each block extending through the blocks, the supporting base having designating means including openings therein registering with the through openings in the blocks for the reception of pegs extending through the blocks for securing the blocks in predetermined positions on the base member and a warp beam rotatably mounted in parallel relation to the rotatable base.

76 10. A device of the character described comprising an annular rotatably mounted supporting base and a plurality of rectangular arcuate blocks

each having a plurality of equally spaced holes in rows at right angles to each other and parallel to the edges of the blocks for the reception of pegs about which warp and weft threads are adapted to be wound during weaving, the rows of holes along the edges of the edges of adjacent blocks being spaced the same distance from each other as from other adjacent rows, some of the holes at each corner of each block extending through the blocks, the supporting base having designating means including openings therein registering with the through openings in the blocks for the reception of pegs extending through the blocks for securing the blocks in predetermined positions on the base member, a warp beam rotatably mounted in parallel relation to the rotatable base and means for restraining the rotation of the warp beam.

10. A hand weaving device of the character described comprising a block having an intermediate body portion, upper and lower portions, the upper and lower portions each having a plurality of equally spaced projections in rows at right angles to each other, the projections on the upper portion being opposite those on the lower portion, there being through peg receiving openings extending through the opposite projections and the intermediate body portion, and a plurality of pegs adapted to be removably inserted into said openings in predetermined positions to outline varying borders of an article to be woven with warp and weft threads, the openings in the block being in equally spaced rows at right angles to each other while the openings in the rows are spaced from each other a distance equal to the distance between rows, each opening being at a junction between two rows at right angles to each other thus permitting the positioning of properly spaced pegs to form varying outlines of the article to be woven.

11. A hand weaving device of the character described comprising a block having an intermediate body portion, upper and lower portions, the upper and lower portions each having a plurality of equally spaced projections in rows at right angles to each other, the walls of said projections tapering outwardly from the body, the projections on the upper portion being opposite those on the lower portion, there being through peg receiving openings extending through the opposite projections and the intermediate body portion, and a plurality of pegs adapted to be removably inserted into said openings in predetermined positions to outline varying borders of an article to be woven with warp and weft threads, the openings in the block being in equally spaced rows at right angles to each other while the openings in the rows are spaced from each other a distance equal to the distance between rows, each opening being at a junction between two rows at right angles to each other thus permitting the positioning of properly spaced pegs to form varying outlines of the article to be woven.

12. A device of the character described comprising a square support having a plurality of equally spaced holes in rows at right angles to each other for the reception of pegs about which warp and weft threads are adapted to be wound during weaving, said rows of holes being parallel to the edges of the support, the distance between each edge of the support and the adjacent row of holes being equal to one half the distance between adjacent rows of holes, whereby a plurality of supports may be assembled so that the distance between adjacent rows of holes of two supports

placed side by side are as equally spaced from each other as those in the other portions of the supports and means for securing adjacent supports to each other.

- 5 13. A hand weaving device comprising a block having a plurality of pin receiving holes and a plurality of pins adapted to be removably inserted into said holes in predetermined positions to outline varying borders of an article to be woven with warp and weft threads, the holes in the block being in equally spaced rows at right angles to each other while the holes in the rows are spaced from each other a distance equal to the distance between rows, each hole being at a junction between two rows at right angles to each other thus permitting the positioning of properly spaced pins to form varying outlines of the article to be woven.
- 10 14. A hand weaving device comprising a block having a plurality of pin receiving holes and a plurality of pins adapted to be removable inserted into said holes in predetermined positions to outline varying borders of an article to be woven with warp and weft threads as well as the outline of a design within the article, the holes in the block being in equally spaced rows at right angles to each other while the holes in the rows are spaced from each other a distance equal to the distance between rows, each hole being at a junction between two rows at right angles to each other thus permitting the positioning of properly spaced pins to form varying outlines of the article.

- 15 15. A hand weaving device comprising a block having a plurality of pin receiving holes and a plurality of pins adapted to be removably inserted into said holes in predetermined positions to outline varying borders of an article to be woven with warp and weft threads, one set of threads being passed about oppositely disposed pins while the other set of threads are passed about other oppositely disposed pins transversely to the first threads and interwoven with the first threads during the passage from pin to pin, the holes in the block being in equally spaced rows at right angles to each other while the holes in the rows are spaced from each other a distance equal to the distance between rows, each hole being at a junction between two rows at right angles to each other thus permitting the positioning of properly spaced pins to form varying outlines of the article and a design to be woven therein and interwoven therewith.

- 20 16. A hand weaving device for weaving an article having a body portion and a design portion interwoven therewith, each portion being woven of a single set of parallel longitudinal threads and a single set of parallel transverse threads, at least one set of interwoven threads in the body and design portion merely extending to the junction of the body and the design and interwoven with each other at the junction, a peg supporting block having a plurality of holes and a plurality of pegs adapted to be removably seated in holes in said peg supporting block, the said holes being in equally spaced parallel rows extending longitudinally and transversely of each other so there is provided a hole at the junction of each longitudinal row with a transverse row as well as at the crossing of each longitudinal row with a transverse row, the arrangement being such that openings for the reception of pegs forming the outline of variously shaped articles as well as the outline of variously shaped designs in said first outline about which threads of the

11

design and body may be wound and interwoven with each other.

17. A device for weaving an article having a body portion woven of warp and weft threads with a design of warp and weft threads interwoven with the woven body portion at the junctions thereof to form an integral part of the article, said device comprising a peg supporting block having a plurality of holes and a plurality of pegs adapted to be removably seated in holes in said peg supporting block, the said holes being in equally spaced parallel rows extending longitudinally and transversely of each other so there is provided a hole at the junction of each longitudinal row with a transverse row as well as at the crossing of each longitudinal row with a transverse row, so that pegs inserted in any hole at the cross over of a longitudinal row and a transverse row is in position for winding a body weaving thread and a design weaving thread around the said peg and interweaving with each other the threads of the body portion and the

12

design at their junction during the passage of one of said threads around the peg, and other pegs beyond the pegs about which threads of the body portion and the design portion are wound and interwoven around which the ends of the threads forming the body of the article beyond the design are wound.

HYMAN M. ZIPPEL.
